UNITED STATES PATENT OFFICE.

MICHAEL DEERING, OF SYRACUSE, NEW YORK, ASSIGNOR TO CHRISTOPHER C. BRADLEY, OF SAME PLACE.

POWER-HAMMER.

SPECIFICATION forming part of Letters Patent No. 355,146, dated December 28, 1886.

Application filed October 16, 1886. Serial No. 216,418. (No model.)

To all whom it may concern:

Be it known that I, MICHAEL DEERING, of the city of Syracuse, in the county of Onondaga and State of New York, have invented 5 new and useful Improvements in Power-Hammers, of which the following is a specification.

This invention relates to that class of power-hammers which are driven by a slack belt and provided with a tightener-pulley and a brake 10 operated by a treadle in such manner that the same movement of the treadle which tightens the pulley against the belt and starts the hammer releases the brake, while upon releasing the treadle the tightener-pulley is released and 15 the brake is applied, thereby stopping the hammer.

The object of this invention is to provide ready means for rendering the tightener-pulley adjustable, so that it can be applied to 20 either side of the belt, as circumstances may require, and so that it can be adjusted toward and from the belt; also, to make the treadle adjustable, so that it can be raised and lowered.

My invention consists to that end of the improvements which will be hereinafter fully set forth, and pointed out in the claims.

In the accompanying drawings, Figure 1 is a side elevation of a power-hammer provided with my improved belt-tightener arranged to 30 bear against the left-hand side of the belt. Fig. 2 is a horizontal section in line xx , Fig. 1. Fig. 3 is a vertical section in line yy , Fig. 2. Fig. 4 is a vertical section in line zz , Fig. 1, on an enlarged scale. Fig. 5 is a fragmentary side elevation, showing the tightener-pulley arranged to run against the right-hand side of the belt.

Like letters of reference refer to like parts in the several figures.

40 A represents the frame of the hammer, B the anvil, C the hammer-head, D the helve, e the horizontal driving-shaft, and E the connecting-rod whereby the helve is operated from the driving-shaft, all of an ordinary or 45 suitable construction.

F represents the driving-pulley, secured to one end of the driving-shaft e in the usual manner, and f represents the slack belt by which the power is transmitted to the pulley 50 F from a line-shaft overhead, which is not shown in the drawings.

g represents the tightener-pulley, mounted on the upper end of the long arm g' of a lever, G, which is journaled upon a horizontal arbor, h . The latter is secured to the frame A 55 on the inner side of the pulley F.

i and i' represent two upright short arms formed on opposite sides of the hub I of the lever G, and J is a connecting-rod, which can be connected with either of the arms i i' for 60 actuating the lever G.

K represents the treadle, which extends in the form of a bow around the anvil B, in the usual manner, and which is pivoted upon a transverse shaft, k , extending through the 65 lower portion of the frame A.

L represents an elbow-lever, secured to one end of the shaft k near the driving pulley F, and having its lower horizontal arm, l , connected with one end of the treadle, while its 70 upper arm, l' , is connected with the rod J, so that the tightener-lever G is actuated by the treadle through the medium of the elbow-lever L and rod J. The upper arm, l' , of the elbow-lever L is provided with a horizontal 75 slot, m , in which the front end of the rod J is adjustably secured by a bolt, m' . By adjusting the rod J on the arm l' the lever G is swung on its pivot, thereby adjusting the tightener-pulley g toward and from the belt, as may be 80 necessary to produce the proper tension on the belt.

The treadle K is secured to the lower arm, l , of the elbow-lever L by a pivot-bolt, n , and an adjusting-bolt, n' , the latter passing through a 85 segmental slot, n^2 , formed in the lower arm, l , of the elbow-lever concentric with the pivot-bolt n .

O represents the brake-pulley secured to the opposite end of the driving-shaft e , and P represents the brake-lever which is secured to the 90 shaft k adjacent to the brake-pulley, so as to bear against the front side of the brake-pulley when the brake is tightened. The lever P is provided with a horizontal arm, p , which extends forwardly from the shaft k , and to which the adjacent end of the treadle is secured by a pivot-bolt, q , and adjusting-bolt q' . The latter passes through a segmental slot, q^2 , formed in the arm p concentric with the pivot-bolt q . 100 The pivot-bolt n is arranged in line with the pivot-bolt q , and the adjusting-bolts n' and q'

are also arranged in line with each other, so that upon releasing the adjusting-bolts $n' q'$ the treadle K can be swung on the pivot-bolts $n q$, thereby raising or lowering the front end of the treadle, as may be desired, without disturbing the adjustment of the tightener-lever G and brake-lever P. When the treadle has been adjusted, it is clamped in position by the adjusting-bolts $n' q'$, whereby the treadle is rigidly secured to the elbow-lever L and brake-lever P, so as to swing on the shaft k as a fulcrum.

R represents a weighted arm secured to the brake-lever P, and extending backwardly from the fulcrum thereof, so as to raise the treadle and apply the brake when the treadle is released.

When the tightener-pulley g is required to bear against the left-hand side of the driving-belt, the connecting-rod J is attached to the upper arm, i, of the tightener-lever G, as represented in Figs. 1, 2, and 4. When the tightener-pulley is required to bear against the right-hand side of the driving-belt, the tightener-lever G is reversed and the connecting-rod J is attached to the lower arm, i', of the lever, as represented in Fig. 5. In either arrangement of the parts the tightener-pulley and brake are applied by depressing the treadle and released by releasing the treadle. The hammer is by this means readily adjusted to correspond with the direction in which the line-shaft rotates from which the hammer is driven.

I claim as my invention—

1. In a power-hammer, the combination, with the driving-pulley and treadle, of a reversible tightener lever and pulley, substantially as set forth.

2. In a power-hammer, the combination, with the driving-pulley and treadle, of a reversible tightener lever and pulley and an adjustable rod whereby the treadle is connected with the reversible tightener lever, substantially as set forth.

3. In a power-hammer, the combination,

with the driving-pulley and treadle, of a reversible tightener-lever, G, provided with two arms, i i', on opposite sides of its fulcrum, and a rod, J, whereby the treadle is connected with either of the arms i i', substantially as set forth. 50

4. The combination, with the elbow-lever L, tightener-lever G, and connecting-rod J, of the treadle K, pivotally connected with the elbow-lever L, whereby the front end of the treadle 55 can be raised and lowered, substantially as set forth.

5. The combination, with the tightener-lever G, connecting-rod J, elbow-lever L, and brake-lever P, of the treadle K, adjustably connected 60 with said elbow-lever and brake-lever, whereby the front end of the treadle can be raised and lowered, substantially as set forth.

6. The combination, with the brake-lever P and elbow-lever L, of a treadle adjustably attached to said brake-lever and elbow-lever, a removable tightener-lever, G, and an adjustable connecting-rod, J, whereby the elbow-lever L is connected with the reversible tightener-lever G, substantially as set forth. 65

7. The combination, with the elbow-lever L and brake-lever P, provided, respectively, with segmental slots $n^2 q^2$, of the treadle K and fulcrum-bolts $n q$ and adjusting-bolts $n' q'$, whereby the treadle is adjustably secured to said 75 elbow-lever and brake-lever, substantially as set forth.

8. The combination, with the reversible tightener-lever G, provided with arms i i' on opposite sides of its fulcrum, of a connecting-rod, J, an elbow-lever, L, provided with slots m and n^2 , a bolt, m', by which the connecting-rod is adjustably secured in the slot m, a treadle, K, and a fulcrum-bolt, n, and adjusting-bolt n', by which the treadle is adjustably 80 secured in the slot n^2 , substantially as set forth.

Witness my hand this 29th day of September, 1886.

MICHAEL DEERING.
